MATCHBOX DISPENSER

Filed Nov. 10, 1949

2 SHEETS—SHEET 2

Fig. 4.

Fig. 3.

A technical line drawing of a rectangular frame structure, likely a component of a larger assembly. The frame is defined by a thick outer border. Several internal and external dimensions are labeled with numerical values:

- Top edge: 64, 5, 46, 68, 64
- Left edge: 16, 36, 34, 30, 24, 28, 32, 26, 22, 18, 44, 50, 51
- Right edge: 74, 56, 40

The drawing uses hatching and cross-hatching to indicate different parts and shadows within the frame structure.

MATCHBOX DISPENSER

Monroe Horn, Corpus Christi, Tex.

Application November 10, 1949, Serial No. 126,621

2 Claims. (Cl. 206—31)

1

This invention relates to novel and useful improvements in match box dispensers and is a continuation in part of my copending application Serial No. 109,096 which was filed on August 8, 1949.

It is the object of this invention to improve the package and dispenser for matches, toothpicks and structurally similar objects by the addition of members attached to the upper longitudinal edges of the sides of the receptacle, which extend inwardly of the receptacle in a single plane in order to hold the articles in an orderly fashion and to prevent the articles from inadvertently becoming separated from the container or receptacle when the receptacle is pulled an excessive amount through one or the other of the open ends of the retaining tube.

It is another object of this invention to support the sides of the receptacle by means of a fixed baffle strip which is secured at the discharge end of the receptacle to both sides preventing separation of the sides and guiding the articles which are to be dispensed toward the rear and bottom of the receptacle so that they are received in the chute from the back part thereof, whereby overcrowding of the chute is obviated.

Ancillary objects and features will become apparent in following the illustrated form of the invention.

In the drawings:

Figure 1 is a perspective view of a blank showing various fold lines from which the article of the invention is made;

Figure 2 is a perspective view of the blank shown in Figure 1, showing a condition of the parts when the device is partially folded;

Figure 3 is a perspective view of the receptacle in the completely folded position;

Figure 4 is a perspective view of the device, portions being broken away to show internal structure, and;

Figure 5 is a longitudinal sectional view taken substantially on the line 5—5 of Figure 4 and in the direction of the arrows.

In my co-pending application I have illustrated, described and claimed a device dealing with similar subject matter. Added to the subject matter of my co-pending application is a number of features tending to render the article of the invention more satisfactorily operative.

The device consists of two major parts. There is a tube 10 which is essentially conventional in nature having an upper open end 12 and a lower open end 14. The tube is a four-sided member.

A receptacle generally indicated at 16 is slid-

2

ably disposed in the tube, and is capable of passing through either the upper end or the lower end of the tube 12. The receptacle is largely made in a manner similar to the receptacle disclosed in my co-pending application. There is a bottom 18 having a transverse fold line 20 along one end thereof. The material on one side of the fold line is divided into three parts 22, 24 and 26. These parts connected together, form one end of the receptacle. The two members 22 and 26 are superimposed as shown in Figure 3, and held together by any suitable means, as glueing, stapling or the like. The part 24 is disposed on the tab 22 and has its center section glued or otherwise rigidly fixed thereto. Weakened lines 28 and 30, weakened as by perforation or scoring are formed in the part 24 so that the end pieces 32 and 34 may be torn from the center part of the member 24 so as to form a support. Apertures 36 are formed in the support 32 and 34 in order to receive a hook 38, nail or the like which is secured rigidly to an anchored member, as a door, wall or the like. This forms the upper end of the receptacle 16.

The receptacle has sides 40 and 42 respectively which are made by simply folding along longitudinal fold lines provided in the blank (see Figure 1). Along the longitudinal edges of the sides 40 and 42 there is a pair of longitudinal flap members or flaps 44 and 46 respectively. These flaps are employed for a dual purpose. The first is to form a guide-way for the matches 48 during dispensing thereof. The second function is to prevent the matches from inadvertently falling through the open top of the receptacle 16 if the receptacle is pulled outwardly an excessive amount from the tube 10. Therefore, in operation the front wall of the tube 10 does not guide the matches or other articles while they are being dispensed (see Figure 5) but the articles adjacent the front wall of the tube 10 are guided by engagement with the flaps 44 and 46.

The discharge end of the receptacle 16 forms a chute for the articles being dispensed. The blank has a rectangular flap 50 extending from the end opposite the part 24. The rectangular flap 50 is folded along the line 51 until it is perpendicular to the plane of the bottom 18 and the extensions 52 and 54 are folded substantially 90° to the rectangular chute bottom forming flap 50. Thereafter the sides 56 and 60 of the extension 52 and 54 respectively are folded flat against the side 40 and 42 of the receptacle as disclosed in Figure 3. The portions 64 and 66 are disposed on top of the members 44 and 46 when the dis-

charge end of the receptacle 16 is in the closed condition. A weakened portion, as by perforations 53, forms a removable tab. When removed a finger hole 55 is provided for facility of match removal and thereby generally reducing wear of the device.

A pair of flaps 68 and 70 are fixed to the lower edges of the sides 42 and 44 and adjacent the longitudinal flap members 44 and 46. When the sides 40 and 42 are folded substantially 90° to a position substantially 90° with respect to the plane of the bottom 18, the flaps 68 and 70 are superimposed (Figure 4) to form a baffle strip for the matches, preventing them from falling directly into the chute thereby overcrowding the chute at the front part thereof. Another purpose of the strip formed by the flaps 68 and 70 is to rigidify the sides 42 and 40 preventing excess separation of the sides or excess movement of one side with respect to the other.

The side pieces 56 and 60 have slanted edges 72 and 74 respectively which are adapted to engage the front wall of the tube 10 when the discharge end of the receptacle is hingedly operated to the open position. The members 56 and 64 which are actually tabs forming a part of the extensions 52 and 54, form the stop for the lower end of the discharge chute base or bottom 50 when the device is in the discharging condition.

From the foregoing an understanding of the structure and operation of the invention is deemed apparent to those skilled in the art.

Having described the invention, what is claimed as new is:

1. A package and dispenser for matches, tooth picks and structurally similar articles, said package comprising an open ended tube with a re-

ceptacle slidably disposed therein, said receptacle having a bottom, sides, an upper end and a discharge end hingedly connected with said bottom and forming a discharge chute, a hanger operatively connected with said upper end, and a baffle strip forming a part of said discharge end fixed to each side to support said sides and to form a guide for the articles discharged and longitudinal flat members secured to each side to retain the articles in the receptacle when said receptacle is pulled outwardly from said tube an excessive amount.

2. In a package and dispenser combination device, a tube having a receptacle slidably disposed therein, said receptacle having a bottom and an open top, sides secured to said bottom and an upper end together with a lower hingedly connected end which forms a discharge chute, the improvement which consists of means secured to said sides maintaining them fixed with respect to each other when said bottom is in the discharging condition, and members secured to the upper longitudinal edges of said sides and projecting inwardly toward each other to form a guide for the article dispensed.
